UNITED STATES PATENT OFFICE

GEORG SCHRÖDEL, OF NUREMBERG, GERMANY

TOY GUN

Application filed August 1, 1927, Serial No. 209,815, and in Germany August 9, 1926.

This invention relates to toy-guns with pyrophorous-igniter, in which after the trigger has been pulled igniting sparks appear in the barrel-mouth.

5 It has become known in toy-guns to make a scraping iron pass over a cerium-stone the action surface of which is arranged parallel to the longitudinal axis of the barrel, said scraping iron being mounted on a movable 10 element of the gun so that in the barrel-mouth a quantity of sparks is produced.

The novelty consists mainly in fitting the movable element of the gun with a scraping knife, i. e. with a tool which is comparatively 15 thin and comprises as active means only one single cutting edge the cerium-stone being, compared with its thickness, of great length and having its longitudinal axis parallel to the barrel. The first mentioned difference is 20 of fundamental importance in constructional respect, as it is much more simple and cheaper to mount on the gun a scraping knife, having only one scraping edge, than to arrange a file on the envelope of the projectile. This 25 difference produces however a surprising effect as regards toy-technics. When the projectile is propelled it comes frequently in touch with the ground so that foreign bodies or moistness will adhere to the scraping tool 30 whereby the production of sparks is prevented or impaired. The larger the roughened surface of the scraping tool is, the more will the adhering of foreign bodies be favoured.

A toy-gun, according to the invention is 35 illustrated by way of example, in the accompanying drawings.

Fig. 1 shows a toy-gun in longitudinal section.

Fig. 2 is a section on line 2—2 of Fig. 1.

40 Fig. 3 shows in side elevation, partly in longitudinal section, a modified manner of mounting the bar which carries the cerium-stone.

Fig. 4 shows in side elevation a similar 45 spark producing device.

Fig. 5 is a section on line 5—5 of Fig. 4.

Fig. 6 shows in side elevation and partly in longitudinal section a spark-producing device for pop-guns.

50 Fig. 7 shows in side elevation, partly in

longitudinal section, a toy-gun with an arrow as projectile.

Fig. 8 shows the arrow on larger scale in side elevation partly in longitudinal section.

Referring to Figs. 1 and 2 a box-shaped 55 casing *c* open at the top-end is fixed near the front end of the barrel *b* mounted in the butt-end *a*. In the casing a cerium-stone *e* is located which is pressed in upward direction by a blade spring *d*. The cerium-stone *e* is 60 mounted in a bar *f* of dove-tailed cross section and projects through an aperture *g* of the barrel, said aperture being shorter than the bar *f* so that the cerium-stone is prevented 65 from projecting too far into the barrel. A metal-sleeve *l* is mounted on the rear end of the shaft of the arrow which has on its front 70 end a rubber-sucker *h*. The metal-sleeve *l* has a flange *k* against which bears a spiral-spring *m*. The flange *k* of steel serves as 75 scraping tool so that, when it is passing along the cerium-stone *e* a strong quantity of sparks is produced in the barrel-mouth.

The form of construction shown in Fig. 3 shows the modification that the bar *f*, in 75 which the cerium-stone *e* is mounted, is arranged on a blade-spring *n* fixed on a clip *o* designed to be pushed over the barrel *b*, this form of construction being simpler than that shown in Figs. 1 and 2.

A similar spark-producing device is shown 80 in Figs. 4 and 5. The casing *c* in which the cerium-stone *e*, the blade spring *d*, and the cerium-stone-carrier *f* are located, is fixed on a slit-ring *p* which encloses the barrel *b*. The ring *p* has a bayonet-slot, composed of a horizontal branch *q* and of a vertical branch *r* so that it can be pushed over a stud *s* mounted 85 on the barrel and serving as front-sight for aiming. When the ring is then turned on the barrel so that stud *s* engages with the vertical branch *r* of the bayonet-slit, the cerium-stone engages with the aperture *g* of the barrel.

Fig. 6 shows a form of construction designed 90 for pop-guns, in which a cork serves as projectile. On the front plate *t* of the piston *u* a scraper *v* is fixed which is designed to pass over the cerium-stone *e*, so that, after 95 the cork *w* has been propelled by the com- 100

pressed air, a spark quantity is produced on the barrel-mouth.

In the toy-gun shown in Fig. 7, an arrow *i* serves as projectile. This arrow *i* has at the 5 rear end a brass cap *l* with a flange *k*, the arrow being retained by the trigger-hook *w*, gripping over said flange.

The arrow is shown in Fig. 8 in enlarged 10 scale. In order to make the arrow adapted for the production of sparks a sleeve *y* of steel is arranged in front of the cap *l*, said sleeve carrying an annular scraping knife *z*.

The scraping knife might also be flexible 15 so that it strongly presses onto the cerium-stone. The propelling spring might be constructed to serve as scraping knife, its front end having a downwardly projecting extension. As this extension is flexible, the cerium-stone can be stationary.

20 Sharpened disks serving as scraping knives might also be mounted on the propelling spring.

I claim:—

1. A toy-gun provided with spark producing means, comprising in combination with a 25 barrel having an aperture in its wall, a casing, a spring adapted to press said casing against said barrel, and a cerium-stone parallel to the longitudinal axis of said barrel 30 and mounted in said casing.

2. A toy-gun provided with spark producing means, comprising in combination with a barrel having an oblong aperture extending in longitudinal direction, and an arrow 25 adapted to be projected from said barrel, a cerium stone projecting through said aperture into the barrel parallel to the longitudinal axis of said barrel, a spring adapted to press said stone into the aperture of said 40 barrel, a flange on the shaft of said arrow adapted to strike against said stone in passing on said arrow being projected from said barrel.

In testimony whereof, I affix my signature.

45 GEORG SCHRÖDEL.
